RAILWAY TIE PLATE

Lawrence P. Allen, Needham, Mass.

Application June 7, 1950, Serial No. 166,622

7 Claims. (Cl. 238—299)

1

The present invention relates to railway tie plates in general, and more particularly to a new and improved tie plate construction which greatly prolongs the useful life of the railway ties with which it is used, and reduces tie maintenance costs.

One of the most important items of railway maintenance cost is the annual tie renewal cost. Considering the high average renewal cost per tie, installed, and the millions of ties which require renewal yearly, the importance of any appreciable increase in useful tie life, even from the standpoint of economy alone, will be readily appreciated. The present invention is of particular importance from the foregoing standpoint.

The various tie plates currently in common use have a serious drawback insofar as concerns their abrading and cutting and wearing effect on the wooden ties on which they rest, which effect has always been a major factor limiting useful tie life. These tie plates are ordinarily of rectangular form, are sharply cornered, and include a horizontal under surface bordered by and abruptly terminating in substantially vertical end and side walls extending across the full height or thickness of the plate metal. This rather abrupt change in plate configuration from the horizontal to the vertical, frequently accompanied by the presence of generally sharp corners and edges, enables the plates under the severe pounding action of the passing wheel-trucks of the rail traffic readily to settle down into the surfaces of the ties, digging for themselves correspondingly shaped recesses or pockets in those surfaces; pockets edged by severed, frayed and crushed wood fibers.

The problem is complicated by the well-known vertical wave-motion set up in the supported rails under the influence of the passing heavily-loaded wheel-trucks, which wave-motion causes the tie plate to move vertically downwardly and upwardly each time a wheel truck passes.

When the track is originally installed, the base of the rails is held firmly to the tie plate and the latter is held firmly to the tie by the headed spikes driven through the tie plate holes into the wood of the tie.

However, as the new plate cuts its way and settles down into the upper surface of the wooden tie under traffic conditions as aforesaid the heads of the spikes, which do not move downwardly with the plate, are left projecting and spaced above the plate, and thus freeing the plate for vertical and even lateral movement under the flow of traffic.

2

The loosened tie plates have a distinct tendency under load to move sideways (i. e. in the longitudinal direction of the ties) not only on straight sections of track, but particularly on curved sections, and with the plates being embedded in pockets in the wood, the vertical end walls thereof, which are in abutting relation to the sharply bent or severed ends of the wood fibers come into repeated contact therewith further fraying and chipping and abrading the wood, enlarging the pockets and further exposing the tie to the penetration of moisture, grit and the like.

The pockets or recesses gouged or pressed into the tie surfaces by the settlement of the tie plates as aforesaid also tend to collect the moisture, dust, grit and the other substances common to exposed roadbeds. As a result, the intermittent movement of the tie plate under the rail wave-motion sets up a pumping action which causes the pocketed dust, grit, and moisture to penetrate the tie through the frayed, crushed or cut fibers, thus hastening tie rot, further mechanically abrades the tie surface, and indeed wears down the spike portions which extend through the plate holes and hastens the corrosion thereof.

All of these undesirable effects become progressively worse with the passage of time, and before long, expensive and time-consuming track repairs must be undertaken in the interests of safety.

One of the common measures taken to restore damaged track is to relevel the plate-bearing tie surfaces by adzing the ties in situ, thereby providing new but lower seats for the plates. This process is, however, rather costly, involving as it does substantial labor and machine charges, and the withdrawal of track sections from active use for substantial periods of time.

In the usual adzing operation, the crew pulls out the old spikes, removes the rails and tie plates, and plugs the old spike holes with wood. At the same time, the level of the rock ballast between ties in the line of tie plates has to be lowered by excavation sufficiently to accommodate the adzing machine and provide working clearance therefor. The adzing machine is then passed several times over the abraded and pocketed region of each tie, cutting away the splintered and clipped wood to form fresh but lower wood surfaces for seating the tie plates.

In the interests of levelness of rails essential for good track, all the ties have to be cut down uniformly to a new lower level established for the ties which have suffered most from tie-plate damage, and this involves otherwise unnecessary

cutting of many good ties which themselves would not have required resurfacing.

After creosoting the freshly-cut surfaces, the tie plates and the rails are reapplied and spiked in place to these repaired ties.

All of the foregoing is burdensome and costly but it has heretofore proven to be essential, and indeed has had to be repeated periodically despite the increasing difficulty presented by the successively deeper cuts required, all because of the considerable tie damage and wear caused by the tie plates currently in use under actual operating conditions.

It is an object of the present invention to provide a simple but durable tie plate construction which will greatly prolong useful tie life by reducing mechanical wear on the ties, which will hold abrasion and cutting of wood fibers down to a minimum, which will greatly simplify and reduce track maintenance by requiring far less frequent adzing operations, and even none at all, which will progressively resist tie penetration to an ever increasing degree, which can respond readily vertically and laterally to rail movement without damaging the tie, which obviates the formation of moisture and dust-trapping pockets in the tie surfaces, which will safeguard the ties, which eliminates any need for special pads between the plates and ties, which can be readily and easily applied to normal wooden ties without special pre-cutting of those ties, which has great structural strength and will not fail under prolonged use, and which is yet quite economical and simple to produce.

With the above and other objects in view, the present invention in one of its aspects may consist of a tie-plate of thickness the same or less than that of the usual tie-plate and having an elevated and shouldered upper surface for receiving the base of the rail and a flat under surface wide enough to extend across the full width of the tie size with which it will be associated, said flat under surface at its end regions merging gradually into a pair of gently upwardly curved end margins which extend outwardly and upwardly to a level well above the height of the plate metal adjacent said margins, and said flat under surface at its side regions merging gradually into a pair of gently downwardly curved side margins which extend downwardly and outwardly and terminate in edge portions spaced a relatively substantial distance outwardly from the side walls of the tie and at a level appreciably below said flat under surface, said upwardly and outwardly curved end margins and said downwardly and outwardly curved side margins being integral with said plate and merging with each other smoothly and gradually at the corners of said tie plate.

The present invention may be embodied in other specific forms without departing from the spirit of essential attributes thereof, and it is therefore desired that the present embodiment be considered in all respects as illustrative and not restrictive, reference being had to the appended claims rather than to the foregoing description to indicate the scope of the invention.

Referring now to the drawings, wherein like reference characters indicate like parts:

Fig. 1 represents a perspective view of a tie plate constituting an illustrative embodiment of the invention, shown seated on a wooden tie; portions of the plate being broken away to reveal constructional features, and a fragment of the rail supported by said plate being indicated in

dashed-dotted lines, and the spikes being omitted for purposes of clarity.

Fig. 2 represents, on a somewhat smaller scale, an end elevational view of the tie plate shown in Fig. 1, looking at the left-hand end thereof.

Fig. 3 represents a similar side elevational view, looking at the right hand side of the tie plate, but this time showing the spikes and rail.

Fig. 4 is a transverse sectional view of the tie plate shown in Fig. 1, taken on line 4-4 of that figure looking in the direction of the arrows, but drawn to a smaller scale.

Fig. 5 is a similar longitudinal sectional view, taken on line 5-5 of Fig. 1, looking in the direction of the arrows.

The tie plate selected for illustration in the accompanying drawings as an illustrative embodiment of the present invention comprises a single plate 10 preferably made of steel and specially formed and shaped to have the configuration shown in the drawings.

The plate 10 may have a smooth and flat undersurface 11 of generally rectangular shape of width at least as great as the width of the wooden tie 12 with which the plate is to be used, and of sufficient area to keep the unit-area loading from exceeding the safe maximum of the wooden tie 12. The end regions of undersurface 11 merge smoothly and gradually into a pair of upwardly curved end margins 14 which extend outwardly and upwardly to an appreciable extent, preferably to a level well above the upper surface 15 of the adjacent plate metal.

The side regions of the plate undersurface 11, on the other hand, merge smoothly and gradually into a pair of downwardly curved side margins 16 extending downwardly and outwardly and terminating in edge portions 17 spaced a relatively substantial distance outwardly from the side walls of the tie 12, and appreciably below the level of the flat undersurface 11. The arcs or curvatures of curves 16 and 14, however, are preferably less than 90°.

Both the upwardly curved end margins 14 and the downwardly curved side margins 16 merge smoothly and gradually into each other at the corner portions 18 of the tie plate 12; and if desired, those corner portions may be rounded as shown in Fig. 1. The curved margins 14 and 16 may be of uniform thickness from base to tip, or they may taper in thickness as shown in the drawings.

The upper surface of the plate 10 includes a slightly elevated substantially flat rectangular region 19, designed to receive and support the base of the rail 13, bordered by a pair of opposed parallel vertical shoulders 20 spaced to embrace the base of the rail and prevent relative sidewise displacement of tie plate and rail. The plate metal leading up to the rail-engaging shoulders 20 may be gradually curved as shown at 21. The rail-supporting upper surface 19 may be slightly canted with respect to the plate undersurface 11, and may be slightly offset in the longitudinal direction of the plate from the plate vertical centerline, as clearly shown in Figs. 3 and 5, so as to provide the slight inclination and eccentricity ordinarily desired in railway tie-plates.

Any suitable number and types of spike-holes may be provided in the plate, as for example the pair of staggered square holes 22 at the edges of the rail-seat 19, designed to receive the square rail spikes 23 the heads of which will overhang and hold down the base of the rail 13, and the pair of oppositely-staggered round holes 24

located closer to the plate ends and designed to receive screw-spikes 25.

An example of a specific tie plate constructed in accordance with the present invention, and suitable for use between wooden ties 9" wide and a rail having a 6 1/4" wide base, is as follows. The plate may be 10 1/4" wide, and 15" long, edge to edge; the margins may taper in thickness from 3/8" at their base to 1/8" at their tip; the uppermost edges of the upwardly-curved end margins may extend 1 1/8" above the upper level of the adjacent plate metal; and the lowermost edges of the downwardly-curved side margins may extend 1/2" below the top surface of the tie and may be spaced 5/8" away from the side walls thereof.

It will be observed that by virtue of the smooth and even configuration of the under surface of the tie plate, which extends across the full width of the tie, the gradually downwardly curved side-margins which stand away from the tie walls, and the gradually upwardly curved end margins which rise appreciably higher than the height of the adjacent plate metal, all in a single integral plate, there is achieved a tie plate which under actual operating conditions will perform its intended rail-secur ing and load-transmitting functions without tending to gouge into or embed itself in or splinter or otherwise damage or abrade the wooden tie on which it rests.

On the contrary, the tie plate of the present invention, under long continued use, will tend to compact the wood fibers of the tie without cutting them, and make the wood in the critical under-plate region denser, if anything, thus better suiting the tie for its load-bearing purpose.

The gently curved ends 14 of the tie-plate assure minimum alteration and most gradual change of direction in the wood fibers at the plate margins, thus permitting the slight plate settlement that does occur under actual loading to take place without accompanying rupture or splitting of wood fibers. Moreover, it will be noted that as the plate settles down into the upper surface of the tie, the size of contact area between plate and tie increases owing to the presence of the upwardly curved end margins which gradually come in contact with more and more wood surface as settlement progresses. This results in a gradual decrease in unit-area loading as plate-settlement increases, which of course is highly desirable, for this increased resistance to settlement which accompanies progressive settlement tends to stabilize the system and prevent further settling.

The absence of abrupt changes in configuration from horizontal to vertical along the margins of the wood-contacting regions of the plate also eliminates the formation of dirt, grit and moisture-trapping pockets in the tie surfaces, thus appreciably prolonging the useful tie life.

The downwardly extending side margins 16 which stand away from the tie side walls also serve to shield the plate-tie contact area against the entry of grit, dust, stone particles and the like which are usually swept into the air and follow fast-moving rail traffic. This serves to prolong the life of the ties and also of the tie plates.

Furthermore, because of the smoothly and gradually curved nature of the marginal regions of the wood-engaging surface of the tie plate, limited lateral movement of tie plate relative to tie, both in the longitudinal direction of the tie as well as in the longitudinal direction of the rail, such as is believed to be a necessary adjunct to the passage of rail traffic, can take place with-

out damaging or abrading the tie or breaking or cutting the wood fibers thereof.

The upturned ends and downturned sides of the integral plate also greatly increase the structural strength of the plate through the double channel-type form they impart to the plate, being equivalent to two perpendicularly related channels placed back-to-back and having their backs formed integrally with each other. This feature enables the plate of the present invention to be constructed of thinner metal than that ordinarily used for tie plates and yet provide a structure of the same or even greater strength. Furthermore, because of the double curvature at the corner regions of the tie plate of the present invention, those corners are much stronger than in the usual tie plates, and this is of special importance since the tie-plates are usually vulnerable to fracture at these corner regions.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what is hereby claimed as new and desired to be secured by Letters Patent is:

1. In combination with a unitary wooden railway tie of predetermined width having a substantially flat top surface and generally vertical sides, a generally rectangularly-shaped metal tie-plate having an elevated and shouldered upper surface for receiving the base of a rail and a flat generally rectangular lower surface at least as wide as the width of the aforesaid tie seated on the top surface of said tie, said flat lower surface having opposite end regions merging gradually and smoothly into a pair of gently upwardly curved end margins, of less than 90° curvature, overhanging the top surface of said tie and extending outwardly and upwardly to a level well above the top of the tie and at least as high as that of the elevated rail-receiving surface, and said flat lower surface having opposite side regions merging gradually and smoothly into a pair of gently downwardly curved side margins, of less than 90° curvature, extending outwardly and downwardly and terminating in edge portions spaced an appreciable distance outwardly away from the vertical sides of said tie and downwardly from said flat lower surface, the curved end and side margins being integral with said plate and with each other, and smoothly and gradually merging into each other at the corner regions of said rectangularly-shaped plate.

2. In combination with a unitary wooden railway tie of predetermined width having a substantially flat top and generally vertical sides, a generally rectangularly-shaped metal tie-plate having an elevated and shouldered upper surface for receiving the base of a rail and a flat generally rectangular lower surface at least as wide as the width of the aforesaid tie seated on the top of said tie, said flat lower surface having opposite end regions merging gradually and smoothly into a pair of gently upwardly curved end margins extending outwardly and upwardly to a level well above the top of the tie and higher than the height of the plate metal adjacent said margins, and said flat lower surface having opposite side regions merging gradually and smoothly

into a pair of gently downwardly curved side margins extending outwardly and downwardly and terminating in edge portions spaced an appreciable distance outwardly away from the vertical sides of said tie and downwardly from said flat lower surface, said upwardly curved end margins and downwardly curved side margins being integral with said plate and merging with each other smoothly and gradually at the corner regions of said rectangularly-shaped plate.

3. In combination with a unitary wooden railway tie of predetermined width having a substantially flat top and generally vertical sides, a metal tie-plate having an upper surface adapted to receive and support the base of a rail and a generally rectangularly-shaped flat lower tie-contacting surface seated on the top of said tie, said lower surface being bordered by two gently curved pairs of marginal regions, one pair being gently curved upwardly and the other pair being gently curved downwardly, each pair extending a relatively substantial distance outwardly from the area of surface contact between the tie-plate and tie and terminating in edge portions spaced vertically an appreciable distance away from the top of the tie, the downwardly curved pair of marginal regions standing away from and clear of the vertical sides of the tie in juxtaposed relation thereto, and all of said marginal regions merging smoothly and gradually with said flat lower tie-contacting surface to provide a plate undersurface devoid of any abrupt changes in surface configuration, thereby to minimize plate-induced tie damage under actual operating conditions.

4. In combination with a unitary wooden railway tie of predetermined width having a substantially flat top and generally vertical sides, a metal tie-plate having an elevated and shouldered upper surface for receiving the base of a rail, a flat lower surface at least as wide as the width of the aforesaid tie seated on the top of said tie, said flat lower surface having opposite end regions merging gradually and smoothly into a pair of gently upwardly curved end margins, of less than 90° curvature, overhanging the surface of said tie and extending outwardly and upwardly to a level well above the top of the tie and at least as high as that of the elevated rail-receiving surface, said margins being integral with said plate, and downwardly extending side portions bordering said flat lower surface and spaced apart a distance appreciably greater than the tie width thereby to stand away from and straddle the vertical sides of said tie with ample clearance, said side portions being integral with said plate and with said upwardly curved plate end margins.

5. For use in combination with a unitary wooden railway tie of predetermined width having a substantially flat top and generally vertical sides, a railway tie-plate having an elevated and

shouldered upper surface for receiving the base of a rail and a flat lower tie-contacting surface adapted to be seated on the top of said tie, said flat lower surface having end regions which merge gradually and smoothly into a pair of gently upwardly curved end margins, of less than 90° curvature, extending outwardly and upwardly to a level well above the flat lower surface and at least as high as that of the elevated rail-receiving surface, said end margins being integral with said plate, and said tie-plate having side margins spaced from and out of contact with the tie sides, whereby the surface contact area between tie-plate and tie will increase appreciably as the tie plate settles itself into the top surface of said tie, thereby to resist such settlement to a progressively increasing degree continuously throughout the course of such settlement.

6. In combination with a wooden railway tie having a top surface and generally vertical sides, a unitary tie-plate having an elevated and shouldered upper surface for receiving the base of a rail and a lower tie-contacting surface seated on the top surface of said tie, a pair of gently upwardly and outwardly curved end margins having lower surfaces of less than 90° curvature merging gradually and smoothly into the end regions of the tie-contacting surface of said plate, said margins extending upwardly to a level well above the top surface of the tie and at least as high as that of the elevated rail-receiving surface of the plate and outwardly for an appreciable distance beyond the area of surface contact between the plate and the tie, said margins being integral with said plate.

7. In combination with a wooden railway tie of predetermined width having top and side surfaces, a unitary tie-plate having an elevated and shouldered upper surface for receiving the base of a rail and a lower tie-contacting surface at least as wide as the width of said tie seated on the top surface of said tie, and including a pair of gently downwardly curved side margins of less than 90° curvature merging gradually and smoothly into the side regions of said lower surface, said margins extending downwardly and outwardly and terminating in edge portions spaced an appreciable distance outwardly away from the side surfaces of said tie and downwardly from the area of surface contact between tie-plate and tie, said margins being integral with said plate.
